UNITED STATES PATENT OFFICE.

WILLIAM F. KIESEL, JR., OF ALTOONA, PENNSYLVANIA.

METAL INTERIOR CONSTRUCTION.

No. 866,481.

Specification of Letters Patent.

Patented Sept. 17, 1907.

Application filed November 24, 1906. Serial No. 344,857.

To all whom it may concern:

Be it known that I, WILLIAM F. KIESEL, Jr., a citizen of the United States, residing at Altoona, in the county of Blair and State of Pennsylvania, have invented certain new and useful Improvements in Metal Interior Construction, of which the following is a specification.

This invention relates more particularly to improvements in the manner of constructing metal partitions 10 for the different compartments in the higher grade of steel passenger cars, although I do not wish to confine the invention exclusively to car construction.

My object is to provide means for building up the partitions from plates of steel and to conceal or finish 15 off the seams between the plates in such manner as to present a pleasing appearance and to break up the partitions into panels of more or less ornamental design.

A further object is to provide means for attaching to 20 the partition plates an insulating fire- and sound-proof backing, which upon the reverse side of the partition will also present a finished appearance.

I attain my objects by constructing the partitions in the manner illustrated in the accompanying drawings, in which—

Figure 1 represents, in elevation, the exterior or finished side of a partition embodying my improvements, said partition being capped by a metal cornice molding constructed in the manner described in my co-pending 30 application for improvements in moldings, Serial No. 344,855, filed of even date herewith; Fig. 2, a horizontal section of Fig. 1 where said figure is broken off at the bottom; Fig. 3, a vertical transverse section on the line *a—a* in Fig. 2; and Fig. 4, a fragment showing the 35 reverse side of the partition and the clamping strip between partition sections.

Like numerals designate like parts in the several views.

These metal partitions are intended to be employed 40 in dividing off the compartments in parlor, dining room and other high grade passenger cars. The partitions are formed primarily of metal plates, as indicated at 1, 2, 8 and 9, the meeting edges of which are flanged on the reverse side and bolted together, preferably by 45 riveted joints, with a finishing strip of metal riveted in between joints; the outer edge of which strip will be so formed as to present a finished appearance at the seam. These partition strips break the partition up into panels, the plates between the principal panel 50 strips being either plain or broken up into more or less ornamental designs.

At the left hand side of Figs. 1 and 2, a portion of a panel is shown, said panel being built up from plates 1, 2 and 3; the plates 2 and 3 constituting a framing

for the central plate 1, and being fitted together by a 55 mitered joint and fastened to plate 1 by means of the flanges 4 riveted together with strips 5 between, said strips having exterior beads to fill out and finish off the seam between plates. These strips 5 may be of different metal from the plates 1, 2 and 3, such as brass 60 or aluminium, and the plates 2 and 3 may be further ornamented by forming thereon longitudinal channels to receive inserts 20 to produce inlay effects. The plate 2, which constitutes one side of this panel is riveted to the next panel plate 8, (which in the drawings 65 is illustrated as a curved panel), by means of the flanges 6 riveted together, with a panel strip 7 of T-shaped cross-section fastened between the flanges and overlapping the exterior edges of the plates. This panel strip 7 may also be of different metal from the 70 partition plates. The curved plate 8 may be fastened at its opposite edge to a partition plate extending at right angles to the first panel, or it may have a panel plate secured thereto on a parallel line with said panel, as shown at 9, the panel plate 9 being flanged and attached directly to the side of plate 8, and the joint between plates being finished by the beaded strip 11 riveted in between the flange 10 on plate 9 and the side 75 of plate 8. In this manner the partitions may be built up in any shape desired. They may be finished off at 80 the top by a cornice molding 21 of any suitable design. As a backing for these partition plates, which at the same time will be fire- and sound-proof, I provide panels of asbestos board 12 spaced apart at the ends, or wherever necessary, by strips 13 of the same material, the 85 surface of the asbestos board on the inside of the partition being finished with a thin sheathing 14 of metal or other suitable material, and the asbestos boards and sheathing 14 being riveted together at the ends, as illustrated, to complete the panel. To fasten these inside panels to the partition plates, I provide, at suitable intervals along the panel-division strips 7, eye-bolts 16, said eye-bolts being riveted in between the flanges 16, where the strip 7 is cut away for the purpose, as shown more clearly in Fig. 3. By means of these 90 eye-bolts a clamping plate 15 is set up against the ends of the inside panels to fasten them against the principal partition plates. Where a corner joint is to be made, eye-bolts 18 will be secured in place by transverse bolts 19 and a corner clamping plate 17 employed. 100 By this means a substantial and rigid partition is produced of light construction, with a perfect insulating backing of sound- and fire-proof materials, the whole presenting an artistic exterior finish and a plain, but neat, interior finish for the compartment inclosed by 105 the partition. It will also be understood that the interior sheathing plates 14 may be arranged to produce decorative panel effects for the interiors of compart-

ments, the partition construction herein shown being designed more particularly for dividing off the kitchen compartment from the main saloon in a dining car.

What I claim as my invention and desire to secure by

5 Letters-Patent is:

1. A metal partition comprising plates flanged and bolted together along their meeting edges, in combination with bolts fastened in with said flanges and projecting therefrom at right angles to the plates, and a clamping 10 plate fastened in place by said bolts, whereby the finish for the reverse side of the partition may be secured in place.
2. A metal partition comprising plates flanged and bolted together along their meeting edges, in combination 15 with a strip of metal bolted in between flanges, said strip being partially cut away at intervals, eye-bolts inserted between flanges where said strip is cut away, and a clamping plate fastened in place by said bolts, whereby the finish for the reverse side of the partition may be secured 20 to said plates.

3. A partition comprising metal plates joined together along their meeting edges, bolts fastened to the plates at the joints, an insulating backing set up against the plates, and a clamping plate fastened in place by said bolts to hold the backing in place.

4. A partition comprising metal plates joined together along their meeting edges, and an insulating backing composed of fire proof and sound deadening material secured to the plates at one side.

5. A partition panel built up from metal plates flanged 30 and bolted together at their meeting edges, with beaded strips fastened in between flanges.

6. A metal plate for inside finish having a channel formed thereon, and an insert of a different material secured in said channel.

In testimony whereof I have affixed my signature, in presence of two witnesses.

WILLIAM F. KIESEL, JR.
